UNITED STATES PATENT OFFICE

JOHN J. LEIDIGH, OF MILWAUKEE, WISCONSIN, ASSIGNOR TO THE NATIONAL CASH REGISTER COMPANY, OF DAYTON, OHIO, A CORPORATION OF OHIO, (INCORPORATED IN 1906.)

CREDIT-MARKING APPARATUS.

1,106,463.

Specification of Letters Patent. Patented Aug. 11, 1914.

Application filed February 25, 1907, Serial No. 359,653. Renewed March 14, 1912. Serial No. 683,702.

To all whom it may concern:

Be it known that I, JOHN J. LEIDIGH, a citizen of the United States, residing at Milwaukee, county of Milwaukee, and State 5 of Wisconsin, have invented new and useful Improvements in Credit-Marking Apparatus, of which the following is a specification.

My invention relates to improvements in credit marking apparatus designed more 10 particularly to be used in connection with credit marking systems of the class described in my application, Number 333,890, filed September 10, 1906, and issued April 13, 1909, as Letters Patent No. 917,955, although my present invention may be employed in other systems, and in connection 15 with other punches.

The object of this invention is to provide means whereby the date and the clerk's number 20 will be automatically stamped upon the credit slip when such slip is inserted in the punch preparatory to receiving the credit mark or rating from the central office.

In the following description reference is 25 had to the accompanying drawings in which.

Figure 1 is a perspective view of a credit marking punch with my invention applied thereto. Fig. 2 is a sectional view drawn on the axis of the punch setting crank rod. Fig. 30 3 is a sectional view of the dater. Fig. 4 is a sectional view drawn on line $\alpha-\alpha$ of Fig. 2. Fig. 5 is a detail view of the clerk's key and key holder.

Like parts are identified by the same reference characters throughout the several views.

1 is the punch head, provided with punch pins 2, and arranged to be actuated from a spring 3, operating through sliding collar 5, 40 lever 6 and sleeve 7. The lever 6 is set to compress the spring 3 (preparatory to the punching operation), by means of a crank rod 9, which is rotated to depress the lever until it engages in a notch 10 in a spring actuated armature trip bar, 11 of an electro-magnet 12, which is energized from the central office to release the trip when credit is to be given. The release of the trip permits a 45 reaction of spring 3 and the punches are thereby pushed upwardly through apertures 50 in a plate 13 to a die plate 14, perforating credit marks or characters in a slip of paper previously inserted by the clerk under such

die plate. All this may be constructed in accordance with the structure disclosed in my former application.

In order that the credit slip may also show the date on which the credit was given and the number of the clerk making the inquiry, I have provided the cap plate 16 of the 60 punch casing with a casing 17, open at the bottom and containing a dating type carrying wheel 18 and an inking ribbon 19. The casing of the dater is hinged to the cap plate at 20 and a rod 21 is connected with such 65 casing at an intermediate point near the hinge, and extends downwardly through the cap plate 16 and is connected with a resilient bar 23 within the punch casing. This bar is secured to the casing at 24 near one 70 end and extends into the path of the crank rod 9, in such a position, that on completing its stroke for setting the lever 6 in trip notch 10, the dater casing is depressed to bring the ink ribbon 19 into contact with a ticket 75 resting on pad 26, under pressure exerted through the dated type 27. As soon as the crank rod 9 is released, the resiliency of bar 23 restores the dater to normal position. If 80 desired, a spring 29 may be also employed at the hinge 20 for this purpose. The dater casing is also provided with a guide 30, constituting a key holder, and adapted to receive a removable key comprising a pin 31 85 provided with a number or character at its lower end, which also presses the ink ribbon forcibly on the ticket when the dater casing is depressed, thus causing an imprint to appear upon the ticket indicative of the clerk 90 in charge at the time. On leaving the station the clerk removes his key, and any other clerk acting in substitution at that station is required to insert his individual key. The clerk's identifying mark will therefore invariably appear upon the credit slip or 95 ticket. The key is rigidly held in position between a lip 35 on the guide and the removable cover 36 of the dater casing.

The crank rod 9 is provided with an exterior crank handle 32 whereby it may be 100 operated, and a spring 33 is preferably employed to restore it to normal position after the trip setting operation.

It will be understood that various modifications of the structure shown and described 105 may be made without departing from the

scope of this invention. For example, it is not material with what movable part of the punch mechanism, the dater is connected, nor is it material what style of punching or 5 dating mechanism is employed, although the dater is preferably located exterior to the casing so as to permit its adjustment by the clerk, while the punch is preferably located within the casing and operated only from 10 the credit department.

Having thus described my invention what I claim as new and desire to secure by Letters Patent is,

1. The combination of a credit punching apparatus provided with an electro-magnetic trip mechanism,—the said punching apparatus including a trip setting device, and electrical means for controlling the punching apparatus from a distant point,— 15 and a dater movably connected with the punching apparatus, and operatively connected with the trip setting mechanism, whereby, when the trip setting mechanism is actuated in one direction, the dater will 20 be simultaneously actuated therefrom, said trip setting mechanism being free to return to normal position independently of the trip after setting the latter.

2. The combination of a credit punching 30 apparatus, and a dating apparatus, both operatively arranged with reference to a ticket receiving plate, and connected with each other with limited independent movement, a common connection for actuating 35 both the credit punching and dating apparatus in one direction, and electro-magnetic means controlling the operation of the credit punching apparatus in the other direction from a distant point, said common actuating 40 connection being free to return to normal position.

3. The combination of an inclosing casing, credit punching apparatus within the casing, electro-magnetic devices controlling the 45 operation of the punching apparatus from a distant point, adjusting devices operatively connected with the punching apparatus and extending to the exterior of the casing, a dating apparatus and connections for actuating 50 the same from said adjusting device, said adjusting device and dating device being free to return to normal position, independently of the punching device.

4. The combination of an inclosing casing, 55 spring actuated credit punching apparatus within the casing, trip mechanism controlling the operation of the punching apparatus, a trip setting device operative from the exterior of the casing, electro-magnetic 60 means for releasing the trip mechanism, a dating apparatus, and a member unconnected with the trip setting device and arranged to be actuated thereby during the trip setting stroke to also operate the dating apparatus.

5. The combination of an inclosing casing, a punch within the casing, an exterior punch receiving die, dating apparatus movably mounted on the casing adjacent to the die, a punch setting device extending through the 70 casing wall, and connections, adapted to be actuated by the punch setting device for operating the dating apparatus, said dating apparatus being provided with a socket adapted to receive a removable printing key provided with a type character identifying the operator.

6. The combination of an inclosing casing, provided with an interior punch operating through one wall thereof, a movable date 80 printing device on the outer surface of the casing, a trip mechanism for holding the punch in operative position, electro-magnetic mechanism controlling the operation of the trip mechanism, comprising a crank 85 rod extending through said casing, and a lever within the casing, connected with the date printing device and adapted to be actuated by said crank rod.

7. In a credit authorizing device, the combination with a stamping device, of a punching device, means normally tending to operate said punching device, restraining means normally preventing an operating movement of the punching device, electro-magnetic means for disabling the restraining 90 means to permit an operation of the punching device, means for restoring the punching device to normal restrained position and connections from the restoring 95 means for actuating the stamping device during said restoring operation.

8. In a credit authorizing device, the combination with a punching apparatus, electro-magnetic devices controlling the operation 100 of the punching apparatus from a distant point, adjusting devices operatively connected with the punching apparatus, a dating apparatus and connections for actuating the same from said adjusting device, said 105 adjusting device and dating device being free to return to normal position, independently of the punching device.

9. A credit authorizing device including a spring actuated punching device, trip mechanism controlling the operation of the punching device, a trip setting device, electromagnetic means for releasing the trip 110 mechanism, a dating apparatus, and a member unconnected with the trip setting device and arranged to be actuated thereby during the trip setting stroke also to operate the dating apparatus.

10. A credit authorizing device including a punch, a punch receiving die adjacent 115 thereto, a dating device in juxtaposition to said punch and die, a punch setting device and connections adapted to be actuated by the punch setting device for operating the dating apparatus, said dating apparatus 120

being provided with means for receiving a removable printing key for identifying the operator.

11. A credit authorizing device including 5
a punch, a movable date printing device adjacent thereto, a trip mechanism for holding the punch in operative position, electro-magnetic mechanism controlling the operation of the punch, trip setting mechanism 10 comprising a crank, and a lever connected with the date printing device and adapted to be actuated by said crank.

12. In a credit authorizing device, the combination with a mechanically actuated 15 punch, of a lock for said punch adapted to hold the same in ticket receiving position, electrical means for disabling said lock, printing means adjacent the punch, manually actuated re-setting means for the 20 punch, and connections intermediate the printing and re-setting means whereby the printing means will be operated on the operation of the re-setting means.

13. In a credit authorizing device, the combination with a mechanically actuated 25 punch, of a lock for said punch adapted to hold the same in ticket receiving position, electrical means for disabling said lock, manually actuated re-setting means for the 30 punch and printing means adjacent the punch and operatively connected with the re-setting means.

14. In a credit authorizing device, the combination with a mechanically actuated 35 punch, of a lock for said punch adapted to hold the same in ticket receiving position, electrical means for disabling said lock, manually actuated resetting means for the punch, and printing means adjacent the 40 punch and operatively connected with the resetting means, said printing means including means adapted to identify the operator.

15. In a credit authorizing device, the combination with a mechanically actuated 45 authorizing means, of restraining means for holding the same in ticket receiving position, electrical means for disabling said re-

straining means, manually actuated resetting means for the authorizing means, and 50 a second authorizing means adjacent the first mentioned authorizing means and operatively connected with the resetting means.

16. In a credit authorizing device, the 55 combination with a mechanically actuated authorizing means, of restraining means for holding the same in ticket receiving position, electrical means for disabling said restraining means, manually actuated resetting means for the authorizing means, and a second authorizing means adjacent the 60 first mentioned authorizing means and operatively connected with the resetting means, said second means including means adapted to identify the operator.

17. In a credit authorizing device, the combination with a ticket receiving die member, a mechanically actuated punch in operative relation thereto, a punch retracting device, an automatic lock adapted to move into punch holding position when the punch is retracted, electromagnetic mechanism for releasing said lock, and a second authorizing device operatively connected 70 with said retracting means.

18. In a credit authorizing device, the combination with a ticket receiving die member, a mechanically actuated punch in operative relation thereto, locking means 75 for restraining said punch, electrical means for disabling said restraining means, a punch retracting device for retracting the punch and releasing a ticket when punched, a second authorizing means, adjacent the 80 punch and operatively connected with said retracting device and adapted to be operated thereby during the retracting movement of the punch.

In testimony whereof I affix my signature 85
in the presence of two witnesses.

JOHN J. LEIDIGH.
